EDWIN W. STONE, OF LONGMEADOW, MASSACHUSETTS, ASSIGNOR TO BIGELOW-HART-FORD CARPET COMPANY, OF THOMPSONVILLE, CONNECTICUT, A CORPORATION OF MASSACHUSETTS.

FILE-WIRE-CARRIAGE-CONTROLLING MEANS FOR PILE-FABRIC LOOMS.

Application filed June 26, 1928. Serial No. 288,344.

This invention relates to pile fabric looms and is more particularly directed to means for controlling the pile wire carriage at the end of its travel that the loom may be run 5 at high speed.

In looms for weaving pile fabrics, such as carpets, rugs, and the like, the pile forming wires are successfully inserted in the shed by a rope motion wherein a rope is connected at 10 one end to the carriage and its opposite end is engaged by a spirally grooved rope wheel which is intermittently driven and released.

The pile forming wires are withdrawn from the pile loops by a chain motion wherein 15 the chain is continuously driven in a direction to withdraw the pile wires from the fabric and is provided with catches or similar devices whereby the pile wire carriage may be connected to the chain and released from it 20 at the end of the carriage travel. The carriage itself is provided with devices for engaging the end of the pile wires to effect their insertion and withdrawal.

The constantly increasing demand for 25 wider pile fabrics, such as carpets, rugs, and the like, has introduced problems relative to the control of the carriage motion. On the one hand, the wider fabrics now demanded have slowed up the out-put capacity of the 30 wide pile fabric looms by reason of the increased length of the pile wires and the increased travel of the pile wire carriage and weight of the parts; and, on the other hand, any attempt to increase the speed of the pile 35 wire carriage to facilitate economic production has introduced problems of carriage control, especially at the end of the carriage travel.

One of the objects of the present invention, 40 therefore, is to provide means whereby the pile wire carriage may be reciprocated at high speed and yieldingly checked at the end of its travel to avoid injury to the associated parts.

45 More specifically stated, the invention provides a dash-pot and plunger arrangement located adjacent the end of the pile wire carriage travel and adapted to be actuated by the carriage as it approaches the end of its travel 50 to thereby yieldingly arrest its movement.

The invention and novel features thereof and new combination of parts will best be

made clear from the following description and the accompanying drawings of one good form thereof.

55 In the drawings:

Fig. 1 is a side elevation at one end of a pile fabric loom, showing more particularly the pile wire carriage controlling means and the invention associated therewith;

Fig. 2 is a plan view showing the pile wire carriage as in the act of inserting a pile wire in the pile shed;

Fig. 3 is an enlarged detail, parts being shown in section, and illustrating one good 65 practical form of the invention;

Fig. 4 is a detached perspective detail of the plunger; and

Fig. 5 is a section of the line 5—5 of Fig. 3.

In a pile fabric loom such as herein illustrated, the pile wires are inserted and withdrawn at one side of the loom, and extending laterally from the side of the loom frame is the pile wire carriage frame and the carriage operating mechanism.

Referring to Fig. 1 of the drawings, a portion of the loom frame is shown at 1 and extending laterally therefrom is the carriage frame 2 which may be of any suitable construction for the support of the associated parts.

Extending lengthwise of the carriage frame 2 is the carriage trough 3 which serves as a guideway for the carriage 4 during its reciprocating movements towards and from the selvage of the cloth. Mounted at the outer end portion of the carriage frame for swinging movement about the pivotal connection 5 is the pile wire trough 6, and means are provided, as usual in this type of loom, to move the pile wire trough 6 about its pivotal connection with the carriage frame to receive a pile wire as it is withdrawn from the fabric and then move into a position rearward, as indicated in Fig. 2, for the insertion of the withdrawn pile wire into the pile forming shed, it being understood, of course, that the carriage 4 is provided with suitable devices now well-known in the art for engaging the end of a pile wire to withdraw it from the fabric and insert it in the shed.

The carriage 4 has connected to it the rope motion, comprising the rope or flexible connector 7 which passes about a guide pulley 8

adjacent the loom side and has its end secured to the rope wheel 9 which is spirally grooved or formed with a scroll, as usual. Mounted on the carriage frame is the sprocket 5 wheel 10 which may be continuously driven from a suitable source of power, and passing about the sprocket wheel 10 is the sprocket chain 11 provided with projections 12 at intervals. The sprocket chain 11 is the element that withdraws the pile wire from the fabric by movement of the pile wire carriage 4 outwardly, and, as indicated, it is guided about suitable guide pulleys or sprocket wheels 13 to direct the upper run of the chain in the 10 lower part of the carriage trough 3. The projections 12 are adapted to engage suitable trip devices on the pile wire carriage to move it outwardly in the pile wire trough or guide and then trip or release the carriage for its 15 inward pile wire inserting movement under the influence of the rope motion. It will not be necessary to describe in detail the various means for actuating the rope motion and the chain motion, nor the devices for tripping 20 the carriage from the chain at the end of its outward movement, since these form no essential part of the present invention.

Rising from the inner end portion of the carriage frame is the bracket 14 to the outwardly extending arm 15 of which is pivotally secured at 16 the friction shoe 17 normally under the influence of a spring or springs 18 acting downwardly, as shown. The spring or springs 18 may be variously 35 contrived, but in the present instance of the invention it, or they, surround a limiting pin 19 which is secured to the inner end portion of the friction shoe 17, the construction being such that as the pile wire carriage 4 approaches the inner end of its movement towards the cloth selvage, a shoe 20 on the carriage 4 passes beneath the friction shoe 17 and tends to check its inward movement.

The construction thus far described may 45 be advantageously employed in weaving the narrower pile fabrics, such as carpets and rugs, but where the loom is increased in width to produce the wider grades of pile carpets and rugs, or is to be run at high 50 speed, it is necessary that additional means be employed to bring the carriage yieldingly to rest at the end of its movements.

The movement of the pile wire carriage to 55 insert a pile wire in the shed may be advantageously made at high speed, but in withdrawing the pile wire from the cloth too high speed of withdrawal is liable to injure the fabric by charring or burning, whether the pile wire be of the cutting or 60 non-cutting type. Under these conditions the present invention contemplates in the first place that the high inserting movement of the pile wire carriage shall be yieldingly checked near the end of its inward movement, and, in some cases, it may also be de-

sirable to provide the same character of yielding check for the carriage at the terminal portion of its outward movement, as indicated by Fig. 1.

Mounted in fixed position below the carriage trough 3 near its inner end is the dash-pot 21 and, as shown, the dash-pot 21 may be secured in such fixed position by a sleeve portion 22 secured to the dash-pot in a proper manner as by screws 23. The sleeve 22 has 70 extended therefrom the arms 24 which may be secured to the side frame of the loom by bolts 25. The dash-pot 21 is preferably lined by a cylindrical portion 26, and mounted for reciprocating movement in the dash-pot is the plunger 27 which is constructed and arranged to be actuated by the pile wire carriage 4 as the latter approaches the inner end of its movement, as will more fully appear. 75

As indicated in Fig. 3, the plunger 27 has the plunger stem 28 extending therefrom and its outer portion is connected by a slot and pin device with a lever 29 pivotally mounted at 30 between the carriage trough 3 and the stem 28. The upper end portion of the lever 29 extends across the path of travel of the carriage 4, as indicated at 31, the construction being such that when the carriage 4 is approaching the end of its inward movement it will engage the upper end portion of the lever 29 and effect inward movement of the plunger relative to the dash-pot. 80

The lower end portion of the lever 29 is 90 preferably provided with a slot 32 into which projects a pin 33 extending from the stem 28, to provide sufficient motion between the parts to accommodate the rectangular movement of the plunger and the arcuate movement of the lower end of the lever. 95

The dash-pot 21 has a fluid or air outlet 34, the part of which extending into the dash-pot is controlled by a needle valve 35 threaded into the wall of the dash-pot, as indicated at 36, whereby the rapidity of the outward flow 100 of the fluid or air may be regulated to suit the conditions of use and speed check desired for the pile wire carriage.

The plunger 27 is provided with an automatically controlled inlet, and, as shown in the present instance of the invention, the plunger 27 is provided with an opening 37 at one side of the stem 28 or eccentric thereto, wherein is located a valve which will be automatically seated to prevent the escape of air or fluid as the plunger moves inwardly and will automatically open to permit inflow of air or fluid to the dash-pot when the plunger is moved outwardly. In the present instance of the invention, the automatic valve is constituted as a ball valve, the ball 38 of which may be seated, as indicated in Fig. 3, as the plunger moves inwardly, to thereby prevent the outflow of air or fluid, and will move 110 120 125 130

from its seat to permit the inflow of air or fluid as the plunger is moved outwardly relative to the dash-pot.

The plunger 27 is preferably faced with leather 39, as indicated more clearly in Figs. 3 and 4, and such leather disk may be conveniently secured to the plunger by screws 40 or other suitable connections, an opening 41 being formed in the leather or similar material 10 to permit the discharge of air or fluid as the plunger is moved in the manner hereinbefore described.

Interposed between the inner end of the plunger and the opposed wall of the dash-pot 15 is a conical spring 42 which is of sufficient strength to move the plunger outwardly into its initial position, as indicated by full lines in Fig. 3, when the upper arm of the lever 29 is freed from contact with the pile wire carriage. By forming the spring 42 conical, as indicated, it may be conveniently compressed within its elastic limits inside the dash-pot to occupy little space at the end of the dash-pot as the plunger moves inwardly, the coils of 25 the conical spring at such time seating themselves one within the other.

As the pile wire carriage 4 is positively moved inwardly to insert a pile wire at high speed, it will engage the upper portion 31 of 30 the check lever 29 and force the plunger inwardly relative to the dash-pot. At such time the air within the dash-pot is allowed to escape at the desired rate by the needle valve 35 which may be so regulated as to effectively bring to rest and overcome the momentum of 35 the carriage 4 as it approaches its inward position. At such times, also, the conical spring 42 will be compressed, while the ball valve in the plunger will be seated to prevent the escape of air or fluid. When the pile wire carriage is moved outwardly by the chain mechanism to withdraw a pile wire from the fabric, it will release the upper end of the check 40 lever 29, let the spring expand and move the plunger outwardly to thereby unseat the ball 45 valve, and permit inlet of air or fluid to the dash-pot.

By virtue of the above construction for overcoming the momentum of the pile wire carriage and pile wire it is possible to run the pile wire carriage for the insertion of a pile wire in the shed at increased speed, because the checking movement of the carriage at the inward end of its travel is sufficiently yielding to prevent injury to the parts or possible 50 disarrangement between the pile wire carriage and pile wire as might happen should the carriage be suddenly arrested.

In some cases it may be desirable to provide 55 a similar pile wire checking means to arrest the pile wire carriage at it approaches the outward end of its movement, as indicated at the right Fig. 1. The construction of the dash-pot and plunger and the lever control 60 of the plunger by the pile wire carriage

may all be substantially the same as already described for the like mechanism disposed near the inner end portion of the pile wire movement. As indicated in Fig. 1, however, the dash-pot, which is located below the outer end of the carriage trough, may be secured to the carriage frame by a bracket 43 which may be clamped about the dash-pot by a bolt 70 44 or similar clamping mechanism.

What is claimed is:

1. In a pile fabric loom, the combination of a pile wire carriage, means for reciprocating the carriage to insert and withdraw pile wires, and a pile wire carriage check comprising a dash-pot and plunger, an actuator connected to one of said parts and operated by the pile wire carriage near the end of its movement in one direction to yieldingly overcome the combined momentum of the carriage and connected pile wire. 75

2. In a pile fabric loom, the combination of a pile wire carriage, means for reciprocating the carriage to insert and withdraw pile wires, and a pile wire carriage check comprising a dash-pot and plunger, a lever connected to one of said parts and actuated by the pile wire carriage as it approaches the end of its travel in one direction to yieldingly overcome the combined momentum of the carriage and connected pile wire. 80

3. In a pile fabric loom, the combination of a pile wire carriage, means for reciprocating the carriage to insert and withdraw pile wires, and a pile wire carriage check comprising a dash-pot and plunger, an actuator connected to one of said parts and operated by the pile wire carriage near the end of its movement in one direction to yieldingly overcome the combined momentum of the carriage and connected pile wire, and a conical spring between the dash-pot and plunger 85 permitting substantially full stroke of the plunger into the dash-pot and then returning the parts to initial position. 90

4. In a pile fabric loom having a pile wire carriage which is positively reciprocated to insert a pile wire into the shed and withdraw another pile wire from the fabric, a carriage check comprising a dash-pot member and plunger member, one of which is mounted in fixed position adjacent one end of the carriage travel, a lever connected to the other member and extending into the path of travel of the pile wire carriage for actuation thereby as the carriage nears the end of its travel. 100

5. In a pile fabric loom, the combination of a pile wire carriage for inserting and withdrawing pile wires during weaving, a dash-pot mounted on the loom frame and having an outlet valve, a plunger having a stem extended therefrom, an automatic inlet valve mounted on the plunger to open as the plunger is withdrawn from the dash-pot, a lever connected to the plunger stem and extending into the path of the carriage to be actuated by the 105 110 115 120 125 130

- latter near the end of its travel to yieldingly overcome the momentum of the carriage and connected pile wire that the loom may be operated at high speed.
5. 6. In a pile fabric loom, the combination of a pile wire carriage for inserting and withdrawing pile wires during weaving, a dash-pot mounted on the loom frame and having an outlet valve, a plunger having a stem extended therefrom, an automatic inlet valve mounted on the plunger out of axial alignment with the stem to open as the plunger is withdrawn from the dash-pot, a lever connected to the plunger stem and extending into the path of the carriage to be actuated by the latter near the end of its travel to yieldingly overcome the momentum of the carriage and connected pile wire that the loom may be operated at high speed.
10. 7. In a pile fabric loom, the combination of a pile wire carriage, a carriage trough or guide for the carriage, means for reciprocating the carriage to insert and withdraw pile wires, a dash-pot and plunger below the carriage trough or guide, a lever pivoted between its ends and having one end extended into the path of movement of the carriage and its opposite end adapted to cause telescopic movement of the dash-pot and plunger when the lever is actuated by the carriage.
15. 8. In a pile fabric loom, the combination of a pile wire carriage, a carriage trough or guide for the carriage, means for reciprocating the carriage to insert and withdraw pile wires, a dash-pot and plunger below the carriage trough or guide and provided respectively with outlet and inlet valves, a lever pivoted between its ends and having one end extended into the path of movement of the carriage and its opposite end adapted to cause telescopic movement of the dash-pot and plunger when the lever is actuated by the carriage.
20. 9. In a pile fabric loom, the combination of a pile wire carriage, means for positively reciprocating the carriage to insert and withdraw pile wires, and means including a dash-pot and plunger for gradually easing up the momentum of the carriage and connected pile wire as they approach the end of a reciprocating movement.
25. 10. In a pile fabric loom, the combination of a pile wire carriage, means for reciprocating the carriage to insert and withdraw pile wires, a friction member to engage the carriage near the end of its movement, and a pile wire carriage check comprising a dash-pot and plunger, an actuator connected to one of said parts and operated by the pile wire carriage near the end of its movement in one direction to yieldingly overcome the combined momentum of the carriage and connected pile wires.
30. In testimony whereof, I have signed my name to this specification.

EDWIN W. STONE.
